UNITED STATES PATENT OFFICE.

DONALD W. THORNBURGH, OF HUNTINGTON, INDIANA.

SIGNAL.

Application filed March 7, 1923. Serial No. 223,342.

To all whom it may concern:

Be it known that I, DONALD W. THORNBURGH, a citizen of the United States of America, and resident of Huntington, in 5 the county of Huntington and State of Indiana, have invented certain new and useful Improvements in Signals, of which the following is a specification.

This invention relates to improvements in 10 signals especially of that class used as an indication to deliverymen of merchandise, as to the character and quantity of goods required, and for similar purposes. The object of the improvement is to provide a device of its class that may be mounted out of 15 doors, exposed to the wind in such a manner as not to be disturbed thereby when either in or out of signaling position. Another 20 object is to provide a group of plates that may be secured together and brought selectively and held into position for display.

These objects are accomplished by the construction illustrated in the accompanying drawings, in which:—

25 Fig. 1 is a front elevation of a construction embodying the invention positioned for use, a portion thereof being broken away; and

30 Fig. 2 is a side elevation of the same. The characters appearing in the description refer to parts shown in the drawings and designated thereon by corresponding characters.

The invention comprises a series of signal 35 placards 1, 2, 3 and 4 and a cover 5 grouped flatwise together. The placards are held pivotally at their upper ends upon an eyelet 6 that extends therethrough and which also secures the entire group of placards in a 40 supporting member consisting of a pair of plates 7 and 8 respectively, the placards and cover being held on the eyelet between the plates. The upper ends of the plates are attached together by means of an eyelet 9 which holds said plates in close contact with 45 each other. One of the plates 8 is composed of spring metal and when secured in position by the eyelets, tends to bear against the other plate 7 in the upper portion of the member.

The several placards are of different 50 colors and have displayed thereon legends 10—11 of varying significance. For instance, upon the placard 2 may appear the legend 50 lbs. Ice and may be suitably colored, and upon the placard 4 may be dis-

played a legend showing the numerator 25 and differently colored, etc. The cover 5 and the plate 8 may, if desired, be treated so as to present the same color effect of that 60 part of the building upon which it is mounted so that its presence will be inconspicuous. In the drawing the device is shown secured upon a post 12 by means of two nails 13 and 14 that are driven through 65 the corresponding eyelets 9 and 6 into the post. By coloring the cover and the supporting member to match the color of the post the presence of the device would not be discernable at a considerable distance. 70 Or, the device may be mounted upon the back of the post, and thus be concealed from view.

In utilizing the device the placards are 75 selectively turned upon the supporting eyelet and moved into horizontal position, one of the upper corners of the placard accordingly being moved forcibly in between the plates 7 and 8 where it is frictionally held and thus sustaining the placard in position 80 for display. By positioning the device close to the edge of the post the placards thus displayed may be viewed from either the front or the back of the post. When not displayed the placards are concealed completely 85 by the cover.

What I claim is:—

1. In a signal device of the class described, a supporting means comprising two plates one of which is flexible; a group of placards 90 arranged in successive order one upon the other, and being positioned between said plates; an eyelet extending through the plates and placards upon which the placards are pivotally movable; and a second eyelet 95 securing said plates together at a point spaced apart from the other eyelet so that said placards may be severally turned to horizontal position and sustained in said position by frictional engagement between 100 said plates apart from the other placards.

2. In a device of the class described, a group of placards and a supporting means pivotally connected with the placards, said supporting means consisting of two plates 105 having close contact with each other at their upper ends and between which the placards are secured at the lower ends of said plates, said plates being adapted to engage and frictionally hold the placards 110 when moved into position for display.

3. In a device of the class described, a

supporting means comprising two plates; an eyelet connecting said plates together at their upper ends; a group of placards positioned between said plates at the lower ends thereof; and an eyelet extending through said plates and placards affording pivotal support for the latter, said placards being adapted to be frictionally engaged and held

between said plates when moved into position for display. 10

In testimony whereof I affix my signature in presence of two witnesses.

DONALD W. THORNBURGH.
